DESIGN FOR A KNAPSACK BUNTING

Madeleine L. Murphy, Bronxville, N. Y.

Application March 18, 1942, Serial No. 106,233

Term of patent 7 years

To all whom it may concern:

Be it known that I, Madeleine L. Murphy, a citizen of the United States and resident of Bronxville, in the county of Westchester and State of New York, have invented a new, original, and ornamental Design for a Knapsack Bunting, of which the following is a specification, reference being had to the accompanying drawing, forming a part thereof.

In the drawing:

Fig. 1 is a side elevational view of the knapsack bunting of my design illustrated in carrying position upon the dotted outline of a figure,

Fig. 2 is a front elevational view of the knapsack bunting shown in Fig. 1 in a partially opened position.

Fig. 3 is a rear elevational view of the knapsack bunting shown in Fig. 1, and

Fig. 4 is a top plan view thereof.

I claim:

The ornamental design for a knapsack bunting, as shown.

MADELEINE L. MURPHY.
